UNITED STATES PATENT OFFICE.

MAURICE E. MESSE, OF CLEVELAND HEIGHTS, OHIO.

METHOD OF CLEANING GARMENTS.

1,271,599.

Specification of Letters Patent. Patented July 9, 1918.

Application filed February 2, 1915. Serial No. 5,669.

To all whom it may concern:

Be it known that I, MAURICE E. MESSE, a citizen of the United States, and a resident of Cleveland Heights, county of Cuyahoga, and State of Ohio, have invented a new and useful Improvement in Methods of Cleaning Garments, of which the following is a specification; the principle of the invention being herein explained and the best mode in which I have contemplated applying that principle, so as to distinguish it from other inventions.

The present invention relates to a process for cleaning fabrics, and has more particular reference to the process commonly known as dry cleaning, in which clothes are treated in a mixture of gasoline and soap solution for the purpose of removing dirt and grease from the clothes without causing any shrinking of the same, or any dissolving of the matter in the cloth. To the accomplishment of the foregoing and related ends, said invention, then, consists of the means hereinafter fully described and particularly pointed out in the claims.

The annexed drawing and the following description set forth in detail one approved method of carrying out the invention, such disclosed mode, however, constituting but one of the various ways in which the principle of the invention may be used.

In said annexed drawing:

Figure 1 is a side elevation of one form of the apparatus which may be used for carrying out my improved process, such figure being partially sectioned to show details of construction; Fig. 2 is a vertical section through the discharge conduit; Fig. 3 is a horizontal section through said conduit, on the line 3—3, Fig. 2; Fig. 4 is a section through the filter.

My improved process consists in maintaining a constant flow in the cleaning chamber, thus removing part of the used gasoline and supplying fresh. The gasoline, as it is drawn off, is strained to remove buttons, filtered to take out the lint and hair, and then cleaned so that it may be used again, when it is returned to the cleaning chamber. The essential step in the process is the maintenance of constant flow through the cleaning chamber, which prevents many of the bad effects on the clothes, which are caused by the usual process. My improved method

will be further explained after a description of the preferred type of apparatus.

The preferred apparatus employs several of the features now used in the art, there being provided a closed, cylindrical receptacle 1, within which there is rotatably mounted a foraminous container 2, which is adapted to receive the clothes or fabrics which are to be cleaned. The receptacle 1 is provided with an inlet conduit 3, and a discharge conduit 4, both of which may be controlled by suitable valves 5 and 6, respectively, which normally will be fully opened. Interposed in the inlet conduit 3 is a chamber 7, in which there is mounted a float 8, controlling a valve 9, adapted to entirely close such conduit. This valve may be of any suitable type controlled by the liquid level in the chamber, and the latter will be so placed with respect to the receptacle that it will maintain the level in the receptacle. In the discharge conduit there is a second chamber 10, in which there is disposed a screen or strainer 11, and adjacent to this strainer (see Fig. 3) is an aperture 12 in the side of the conduit, which will be normally closed by means of a plate 13, and a pivoted arm 15, which may be locked by means of a bolt 16 to the chamber. In the arm 15 there is mounted a hand-wheel 17 bearing against the plate 13, and forcing the same tightly against the sides of the aperture 12.

The cleaning chamber 20 is connected to the chamber 10, in which there is mounted a strainer, by means of a conduit 30, and from the chamber 20 there leads a discharge conduit 31 into a storage tank 21, from which the cleaning solution is drawn by means of a pump 22 and returned to the system. In the conduit 30 beyond the chamber 10 there is interposed a chamber 32, in which there is disposed a strainer for the purpose of removing the lint which is taken out of the usual fabric and carried away by the solution. This strainer is also adapted to remove any hair from the solution which comes out of fur goods when the same are cleaned. Any suitable type of strainer may be used for this purpose, although preferably I use a fine cloth similar to that which is used for straining milk, such for example as cheese-cloth. The chamber 32 is also provided with a lateral aperture normally covered by means

of a pivoted cap 34, which may be opened in order to move the strainer when desired for cleaning.

In Fig. 4 there is shown a section of the 5 cleaning chamber 20. The solution is brought to this chamber by means of a conduit 35 which is extended around the interior walls of the chamber and has closed ends, but is provided with a plurality of 10 diagonally downwardly directed apertures 36 which are adapted to permit the discharge of the cleaning solution at an angle of approximately forty-five degrees to the vertical. The means which are employed for 15 cleaning the solution consist of a conical-shaped strainer 37, preferably of cloth, which is mounted at its top upon a suitable frame 38 and is provided with a cover 39. The frame 38 has transversely disposed in- 20 tersecting cross members, at the intersection of which there is mounted a conduit 40 leading through the bottom of the strainer and leading from the chamber 20 into the storage tank 21. This conduit 40 is perma- 25 nently mounted in the chamber 20, the frame 38 being removably attached thereto at the top, while at the bottom of the conical strainer there are mounted two disks 60 and 61, one on either side of the strainer mate- 30 rial, which are held in position on the conduit by means of a lock nut 42 which may be removed and the strainer bodily lifted out of the casing for cleaning and for renewal. Mounted beneath the conical strainer are a 35 number of vertically disposed transverse vanes 44 which are for the purpose of preventing surging of the solution in the chamber, since if the solution is allowed to become quiet much of the dirt will settle out and de- 40 posit upon the bottom of the chamber, when it may be removed through a drain conduit 45. The level of the solution in this filtering chamber 20 is maintained below a given point by means of a safety discharge conduit 46 which leads to a storage tank (not shown). The conduit 40 is closed at its top and is provided with a number of lateral apertures 47 through which the solution 45 when filtered is allowed to discharge.

50 The action of this cleaning chamber is as follows: The solution is discharged laterally from the inlet conduit against the sides of the conical filter, such discharge permitting a certain amount of the solution to imme- 55 diately filter through the cloth and to then discharge through the discharge conduit. The remainder of the liquid settles in the casing 20 outside of the conical filter and gradually seeps through the same, dirt re- 60 maining on the outside of the cloth from which it may be removed at intervals upon removal of the filter. The lateral discharge of the solution against the sides of the cloth serves another purpose, namely, that of 65 creating a slight circulation down the sides.

of the filter and thus cleaning the dirt from the same and taking it to the lower part of the casing when it is permitted to settle between the vanes 44.

At present there are two general methods 70 of dry cleaning. The first of these methods is that employed by the better and more reputable establishments who thoroughly clean the goods, while the second is that employed by the others. In the first of these 75 methods, the clothes are placed in a machine similar to that already described, the most common machine for this purpose being an ordinary laundry washer, which is then filled about one-half full of gasoline and soap 80 solution. The clothes are within the inner container or hopper which is oscillated in either direction through one or two revolutions, thus causing the clothes to be forced through the liquid which secures the clean- 85 ing action. The surface dirt on the clothes, which has not been ground in, is removed almost instantly in this way, but the operation is continued about twenty-five minutes in order to wash out all of the looser dirt. 90 The clothes are then removed from the first machine, and are placed in a centrifugal extract- 95 ing machine of well known type, to rid them of any remaining liquid and dirt and are then placed in the second machine where 100 they are again washed with soap solution in order to remove the dirt and grease which has settled upon and worked into the creases in the cloth. The clothes are then removed and again placed in an extractor when they 105 are given a rinsing in a third machine. The clothes are a third time run through a centrifugal extractor to remove as much liquid as possible before drying.

The disadvantages of the above method 110 are that three separate machines are required for cleaning the clothes, and three separate solutions or three separate baths in one machine. In order to avoid the expense of this machinery and the use of so much 115 solution, many cleaners wash the clothes but once, in the original machine, in which event the washing is continued for thirty or forty minutes in order to remove the dirt in the creases, as well as the surface. It has been 120 found that where this is done, the dirt which is in solution, and the lint which is washed out of the clothes when they are first cleaned, is driven back into the cloth, and it is thought, although it cannot be definitely proved, that the fine dirt is forced into the 125 cells in the wool fabric. It is known that when white or light colored goods are cleaned in this way, they sometimes appear of an appreciably darker color when cleaned, although, of course, the color is evenly distributed and is in the nature of a dye. If this dirt and grease is once driven back into the clothes, and being in suspension, is carried into the wool fabric, it can never again 130

be entirely removed. In this method, the clothes are, it is true, rinsed after the single washing, but this rinsing has no effect in removing the lint which is driven back into 5 the cloth, and the dirt which enters the cells in the wool fiber appreciably darkens the cloth, and also, of course, shortens the life of the fabric and makes the cloth more susceptible to stains and dust spots, and is un- 10 sanitary.

Both of the above methods have a common danger, which is that of explosion of the solution when the clothes are removed from the machines. It is well known that the 15 present process of cleaning generates static electricity in the gasolene and saturated clothes. When the clothes are removed from the machine the circuit is broken, the workman's body forming the ground of the 20 circuit, often making a spark of sufficient strength to effect the ignition of the vapors that have become mixed with air at the opening of the machine. This has already been a source of numerous fires and ex- 25 plosions in this industry, and is common to both of the methods above described.

In my improved process, I secure a much better cleaning than can be secured in the first or second method referred to above, 30 and at less expense, and with less apparatus and solution than is used in the first process mentioned. In the present process the gasolene is caused to move continuously through the receptacle, fresh gasolene being 35 supplied continuously, and the old or used gasolene being drawn off at the same rate. This is assured by means of the float-valve controlling the flow of the gasolene through the conduit 3. This constant change pre- 40 vents the solution from being dangerously charged with electricity. The clothes are first immersed in the liquid, and since the valves 5 and 6 are both open in the apparatus, gasolene is allowed to flow in through 45 the inlet conduit at the same rate that the used gasolene flows out through the discharge conduit.

My entire process consists in first placing the clothes in the container, flooding the 50 same with gasolene and soap solution to the desired level, when the discharge valve 6 is opened, permitting the gasolene to drain away. The container is then moved in such a way as to force the clothes through the liquid, the soap solution and gasolene thus being given an opportunity to wash out all 55 of the dirt and grease from the fabric, but the solution is kept comparatively clean, since fresh gasolene is being added con- 60 tinually. After this action has gone on for some fifteen or twenty minutes, the inlet valve 5 is closed and the entire amount of solution is drained off. The receptacle is then drained, and clear gasolene is supplied 65 for rinsing. This clear gasolene can then be

wholly drained away from the machine, and the clothes can thus be removed and run in the extractor only once, this completing the cleaning process without the danger of starting a fire in the gasolene vapor. It is im- 70 possible, at least impractical, to drain the machines in the other processes for this purpose, since if the machines are drained when the solution contains the dirt which has been removed from the clothes, this dirt 75 would merely deposit on the clothes, and they would be in practically the same state as before cleaning.

A serious difficulty which is met with in all methods of dry cleaning, is that the buttons from the clothes come off, and in the existing apparatus it is very difficult to recover these buttons, since all of them do not drain into the discharge pipe on the same day that the clothes are cleaned. In the 85 present machine the continuous flow from the inlet conduit to the discharge conduit carries the buttons which drop into the machine, into the latter conduit where they are collected against the strainer 11, and can be 90 removed upon opening the plate 13.

My improved process comprises a method for improving the cleaning of the clothes by successively removing the used solution and simultaneously supplying an equal 95 amount of fresh solution to the cleaning chamber. The process also involves a simple but effective method for cleaning gasolene of all of the foreign matter which has been accumulated during the cleaning step, such 100 cleaning being best accomplished by means of successive filters as here used. The number and capacity of the various strainers and filters will of course be proportioned to the amount of solution which is desired to 105 be withdrawn from the cleaning chamber, and can be so arranged that any desired rate of circulation can be maintained.

Other modes of applying the principle of my invention may be employed instead of the one explained, change being made as regards the steps or mechanism herein disclosed, provided the means stated by any of the following claims or the equivalent of such stated means be employed.

I therefore particularly point out and distinctly claim as my invention:—

1. In a method of dry cleaning clothes in a single chamber, the steps which consist in immersing the clothes in a cleaning solution in the chamber, forcing the solution through the clothes by movement of the latter in the former, continuously replacing the solution with solution by drawing off solution from one point of the chamber and simultaneously supplying clean solution to the chamber at another point, then completely drawing off the solution and repeating the operation with clean solution.

2. In a method of dry cleaning fabrics, the 130

steps which consist in immersing the same in a cleaning solution, agitating the solution, continuously drawing off a part of the solution, cleaning the same and then returning it to the original solution.

3. In a method of dry cleaning fabrics, the steps which consist in immersing the same in a cleaning solution, agitating the solution, continuously drawing off a part of 10 the solution, filtering the same and then returning it to the original solution.

4. In a method of dry cleaning fabrics, the steps which consist in immersing the same in a cleaning solution, agitating the 15 solution, continuously drawing off a part of the solution, straining the same, filtering the

same, and then returning it to the original solution.

5. In a method of dry cleaning fabrics, the steps which consist in immersing the same 20 in a cleaning solution, agitating the solution, continuously drawing off a part of the solution, successively straining, filtering and cleaning the same, and then returning it to the original solution.

Signed by me, this 29th day of January, 1915.

MAURICE E. MESSEY.
